UNITED STATES PATENT OFFICE

JOSEPH D. CONLEY, OF CULVER CITY, CALIFORNIA

DESIGN FOR A BOOK END

Application filed June 12, 1929. Serial No. 31,650. Term of patent 14 years.

To all whom it may concern:

Be it known that I, JOSEPH D. CONLEY, a citizen of the United States, residing at Culver City, county of Los Angeles, and State of California, have invented a new, original, and ornamental Design for Book Ends, of which the following is a specification, reference being had to the accompanying drawing, forming part thereof.

Fig. 1 is a top plan view of a book end showing my new design.

Fig. 2 is a view in front elevation of the same.

Fig. 3 is a view in side elevation of the same.

I claim:

The ornamental design for a book end, as shown.

JOSEPH D. CONLEY.
